MARSHALL BARKER, OF HUMPHREY, NEW YORK.

Letters Patent No. 69,386, dated October 1, 1867.

IMPROVEMENT IN ELLIPTIC-SPRING BRACE.

The Schedule referred to in these Letters Patent and making part of the same.

TO ALL WHOM IT MAY CONCERN:

Be it known that I, M. BARKER, of Humphrey, in the county of Cattaraugus, and State of New York, have invented a new and useful Improvement in Elliptic-Spring Brace; and I do hereby declare that the following is a full, clear, and exact description thereof, which will enable others skilled in the art to make and use the same, reference being had to the accompanying drawings, forming part of this specification, in which—

Figure 1 is a side view of my improved brace attached to a pair of elliptic springs.

Figure 2 is a vertical section of the same, taken through the line x x , fig. 1.

Similar letters of reference indicate like parts.

My invention has for its object to furnish an improved means by the use of which elliptic springs may be strongly and securely braced, and which, at the same time, will allow either of said springs to act without a strain upon the other; and it consists of the combination of the brace-rods and small pivoted wheel with each other and with the elliptic springs, as hereinafter more fully described.

This brace is applicable to elliptic or half elliptic-springs wherever they are arranged in pairs, whether beneath the body of a wagon, buggy-seat, or in any other similar situation,

A and B are elliptic springs, about the construction of which there is nothing new. C and D are the brace-rods, the size of which will depend upon the particular place in which they are used. The outer ends of the braces C and D are secured to the centre of the lower parts of the springs, as shown in figs. 1 and 2, and their inner ends are pivoted to the upper and lower sides of the small wheel E, the axle or shaft of which is attached to or revolves in supports or eyes F, securely attached to the middle part of the under side of the box or other body which the springs support. If necessary the under side of the box may be grooved or channelled, as shown in figs. 1 and 2, to allow the brace-rod attached to the upper part of the wheel E to play freely. This brace thus constructed and arranged permits both springs to act together, or either of them to act separately without any strain upon the other; and the coupling being in the centre the sag of the box affects both springs alike.

I am aware of the rejected application of A. Cleveland, filed December 28, 1866, but as this forms no part of my invention I do not therefore claim it.

I claim as new, and desire to secure by Letters Patent—

The arrangement of the brace-rods C D, their outer ends secured to the centre of the lower part of the springs A B, their inner ends pivoted to the vertical wheel E pivoted to the bottom of the wagon-box, as herein described for the purpose specified.
